UNITED STATES PATENT OFFICE.

GEORGE W. GOLDEN, OF DETROIT, MICHIGAN.

SASH-LOCK.

SPECIFICATION forming part of Letters Patent No. 611,246, dated September 27, 1898.

Application filed February 26, 1898. Serial No. 671,744. (No model.)

To all whom it may concern:

Be it known that I, GEORGE W. GOLDEN, a citizen of the United States, residing at Detroit, in the county of Wayne and State of Michigan, have invented certain new and useful Improvements in Sash-Locks, of which the following is a specification, reference being had therein to the accompanying drawings.

This invention relates to locks for window-sashes intended especially to be applied to the meeting-rails thereof, and it is embodied in the parts, arrangement, and combinations thereof, hereinafter described, and particularly set forth in the annexed claims.

15 In the drawings, Figure 1 is a sectional perspective view of the meeting-rails of an ordinary window-sash, showing my invention applied thereto. Fig. 2 is a cross-section at one side showing the stops on the upper sash. Fig. 3 is a section on line $\alpha\alpha$.

20 A and B are the upper and lower sash. The upper sash is provided with lugs, such as b or other securing means or stops, also with a headed stud D at the middle of its meeting-rail.

25 D' is a plate resting on the meeting-rail of the lower sash and adapted to slide to or from the upper sash, being guided on the studs or screws H, which pass through the slots E in the plate.

30 F is a hook pivotally secured on the plate, having a finger-piece by means of which the hook may be turned. The operator grasps the finger-piece on the hook and turns it until the slot G in the hook engages the stud D, when a continued movement of the hook will cause the plate to be drawn across the joint and partially over the rail of the upper sash, the ends being drawn beneath the lugs b and 35 the middle being locked by the engagement of the cam beneath the head of the stud. By this means the plate locks the two sashes together and by being forced down upon the joint between the meeting-rails acts as a 40 weather-strip for the joint.

The plate may be drawn down at the ends by beveling the edges of the plate or the under side of the lugs.

The intermediate points may be drawn down by forming the inclined bearings for 50 the heads of the screws H in the plate.

What I claim as my invention is—

1. In a sash-lock for meeting-rails of sashes, the combination of a plate slidably secured to one sash, a cam pivoted on said plate, a 55 stud on the second sash with which said cam engages for moving the plate, and locking-lugs carried by said second sash into engagement with which said plate is moved by said cam. 60

2. In a sash-lock for meeting-rails of sashes, the combination of a plate provided with a guide-slot, a stud secured to one sash working in said guide-slot, an inclined bearing on said plate engaging with a portion of said 65 stud, locking-lugs on the second sash having faces adapted to engage with the face of said plate one of said faces being inclined, and means for moving the plate into locking engagement with said locking-lugs. 70

3. In a sash-lock for the meeting-rails of window-sashes, the combination with a plate having at each end a beveled edge and guide-slots having inclined bearings at the sides thereof, screws passing through said guide-slots into the lower sash having heads engaging said inclined bearings, locking-lugs secured to the upper sash adapted to engage said beveled edges, a stud D secured to the upper sash, and a cam pivoted to said plate 75 having a slot in which said stud D works, substantially as and for the purposes described. 80

In testimony whereof I affix my signature in presence of two witnesses.

GEORGE W. GOLDEN.
